UNITED STATES PATENT OFFICE.

EDWARD ROSENTHAL, OF CINCINNATI, OHIO.

BALL-AND-BAT GAME.

SPECIFICATION forming part of Letters Patent No. 786,997, dated April 11, 1905.

Application filed June 20, 1904. Serial No. 213,213.

To all whom it may concern:

Be it known that I, EDWARD ROSENTHAL, a citizen of the United States, residing at Cincinnati, in the county of Hamilton and State 5 of Ohio, have invented certain new and useful Improvements in Ball-and-Bat Games, of which the following is a specification.

My invention relates to improvements in ball-and-bat games especially adapted for use 10 in parlors.

The object of my invention is to provide simple, convenient, and economical apparatus for the purpose of producing an interesting and amusing game for scientific and skilful 15 practice and exercise.

My invention consists in a base provided with a standard having a circumferential groove near its top, a flexible cord or the like secured thereto at one end and carrying a ball 20 on the other or free end, and means for giving movement to the ball.

In the drawings, which serve to illustrate my invention, Figure 1 is a side elevation of the standard, cord, and ball and vertical section of the base. Fig. 2 is a perspective view 25 showing the base folded and the standard removed from its socket and placed in position on the base for convenience in carrying and economy of space in packing for shipment or 30 storage.

I prefer to construct the apparatus substantially as shown, with a base of two parts B and C, secured together by hinges I. Upon the base I secure a stationary socket D, into which 35 is placed a removable standard G, having a circumferential groove A near its top, which top is preferably ball-shaped.

I place the base upon a table, stand, or other object to bring the apparatus to a convenient height. Then I insert the standard 40 into the socket, as shown in Fig. 1. The cord H is looped or tied over the top of the standard within the circumferential groove and hav-

ing upon its free end a ball F. A bat E of any convenient construction, preferably flat, 45 is used by the players to hit the ball to drive it in the desired direction and prevent it from going in the wrong direction.

The game is played by two persons, each driving the ball in the opposite direction from 50 the other, the object being to demonstrate skill in causing the cord to wrap or wind around the standard, as shown by dotted lines, Fig. 1, each time the cord is so wrapped counting a point in favor of the player in 55 whose direction the ball turned. It will happen in the progress of the game that two skilful players will keep the cord from wrapping upon the standard for a considerable time, being alternately knocked first in one 60 direction and then the opposite direction, or it may be caused to partially wrap by one player and before the point is scored the other player will drive the ball in the opposite direction, so as to unwind the cord. 65

This game is adapted for use in the house and is of great advantage over games where loose balls are used, as there is no danger of breakage of the furniture and the ball is always in range, so that a continuous game may 70 be had, if desired, while it may be compactly folded when not in use.

I claim—

In a ball-and-bat game, a base formed of two sections of different widths hinged together, whereby an offset is formed when said parts are folded together, a socket on said base near its center, a standard removably secured in said socket, and a ball secured to said standard by a string and adapted to swing 80 therearound, said standard being adapted to rest in said offset when not in use. 85

EDWARD ROSENTHAL.
